UNITED STATES PATENT OFFICE.

OTTO ARAM, OF PHILADELPHIA, PENNSYLVANIA, ASSIGNOR TO WESTINGHOUSE ELECTRIC AND MANUFACTURING COMPANY, A CORPORATION OF PENNSYLVANIA.

UNDERFEED STOKER.

Application filed May 10, 1923. Serial No. 638,119.

- My invention relates to mechanical underfeed stokers, more particularly to underfeed stokers having a relatively great length, and it has for an object to provide in each of the 5 retorts of a stoker of the character designated, auxiliary fuel-feeding mechanism which shall operate with high degree of flexibility and efficiency in the distribution of fuel throughout the fuel bed.
- 10 It has heretofore been proposed to provide mechanical underfeed stokers with a fuel-feeding member in each retort which may be given a variable length of stroke. Such a construction is described in the patent of 15 Elwood E. Taylor, No. 792,862, granted June 20, 1905. The purpose of the present invention is to provide auxiliary feeding means which are adapted for employment in connection with stokers having retorts of 20 greater length than have heretofore been commonly provided. To this end, I employ two auxiliary rams mounted in different portions of the retort and operatively associated with the driving mechanism of the stoker by 25 means of a single externally extending connection in which means are provided for varying the effective feeding capacity of the two auxiliary rams.
- In the drawing, Fig. 1 is a longitudinal 30 sectional view of an underfeed stoker embodying my invention; and Fig. 2 is a sectional view on an enlarged scale of the auxiliary rams and their actuating mechanism; Fig. 3 is a view in longitudinal section of a 35 modified form of the auxiliary ram mechanism illustrated in Fig. 2; and Fig. 4 is a longitudinal sectional view of another modification of my auxiliary ram operating mechanism.
- 40 Referring to the drawing, I show an underfeed stoker of the well known type comprising retorts 11, twyers 12, a hopper 13, and a main ram 14 actuated through a connecting rod 15 by suitable mechanism. On 45 the bottom portion 18 of the retort 11 are supported two separate auxiliary rams 19 and 20, the ram 19 being forward of the ram 20. The ram 19 is arranged to be reciprocated by means of a rod 23 which, as illustrated, may take the form of a tube or pipe. 50 The rod 23 is preferably disposed beneath the retort 11 and extends outwardly through the forward part of the stoker setting. The outer end of the rod is provided with any suitable mechanism for causing a reciproca-
- tion thereof. As shown a lever 24 fulcrumed at 25 engages the stops 26, 27, secured to the end of the rod. The stops 26 and 27 are preferably adjustably secured to the rod 23 in any suitable manner. As shown, pins 29 60 passing through the stops 26 and 27 and holes 30 in rod 23 serve to secure the stops 26 and 27 at varying positions along the rod 23. The upper end of the lever 24 is provided with a longitudinally extending slot 65 which receives a wrist pin 31 of the ram 15, which connection serves to cause an oscillation of the lever 24 and a reciprocation of the rod 23.
- To the inner end of the rod 23 is permanently secured a yoke member 35, the arms 36 of which are connected to a lug 37 depending from the lower side of the auxiliary ram 19 and extending through a slot 38 in the bottom of the retort 11. A rod 40 is 70 secured at one end to a lug 41 depending from the auxiliary ram 20 and passing through a slot 42 in the bottom of the retort 11. The other end of the rod 40 is connected to the ram 19 and the rod 23 by 75 means of a lost-motion device which should be of such character as to permit of an equal movement of the two rams or a variable movement thereof as conditions of operation require. As illustrated, the rod 40 passes between the arms 36 of the yoke 35 and extends telescopically into the tube 23. A movable stop 44 is secured to the rod 40 in such relation with respect to the yoke member 35 as to give the desired difference in stroke between the rams 19 and 20. The stop 44 may be secured to the rod 40 in any suitable manner, as by means of pins 45 extending through the holes 46 in the rod 40. The yoke member 35 is provided with a depending lug 48 and the stop member 44 with a similar depending lug 49. A bolt 50 passes through the lugs 48 and 49 and is provided at its ends with nuts 51 which permit a proper adjustment of the relative positions 80 of the two rams.
- In the construction above described two 85 separate mechanisms are provided for regulating the length of the strokes of the rams 19 and 20. The lost-motion mechanism associated with the outer end of the rod 23 is so constructed that at the beginning of each rearward stroke the rod assumes its extreme uppermost position so that the auxiliary ram 19 at all times begins its rearward or 90
- 100 105 110

pushing stroke from its uppermost position in the retort. The extent of the reciprocation of the rod 23, and hence of the ram 19, is regulated by the movement of the stop 27 along the rod 23, in such a manner that any stroke of the ram 19 from no movement to its maximum reciprocation may be obtained. The second lost-motion mechanism is likewise constructed so that the lower 10 auxiliary ram 20 begins its pushing stroke from its uppermost position. To effect any desired adjustment of the lower ram 20 from no motion to a stroke equal to that of the auxiliary ram 19 requires only a proper 15 setting of the stop member 44 with respect to the rod 40 and an adjustment of the nuts 51 on the rod 50 to engage the depending lugs 48 and 49 when both the rams 19 and 20 are in their uppermost position. By reason 20 of the above arrangement both the upper ram 19 and the lower ram 20 begin their effective strokes from their uppermost positions and in case the lost-motion mechanisms are so adjusted that either one or 25 both of the auxiliary rams 19 and 20 are given no reciprocating motion, they remain in their uppermost positions, where they are the better protected from the heat of the furnace. The uppermost positions of 30 the auxiliary rams may be adjusted to meet varying conditions of operation by a movement of the stop 26 along the rod 23.

In Fig. 3, I show a modified arrangement

35 of the operating mechanism for the auxiliary rams. A single driving or connecting rod 61 is connected at its lower end to the depending lug 41 of the lower auxiliary ram and at its upper end to the main ram-driving mechanism in a manner similar to that 40 described above in connection with Fig. 1.

The upper auxiliary ram 19 has a depending lug 65, which is adapted to engage a stop member 66 secured to rod 61 at a point which will carry the auxiliary ram 45 19 to its foremost position at each forward reciprocation of the rod 61. An adjustable stop member 67 may be secured to rod 61 at a plurality of positions by means of bolts 68 which pass through the stop member 67 50 and holes 69 in the rod 61. The adjustment of the stop member 67 along the rod 61 regulates the length of the stroke of the auxiliary ram 19.

As in the construction of Fig. 1, each of 55 the auxiliary rams 19 and 20 is returned to its upper position on the forward stroke of the rod 61. In this modification, however, the lower ram 20 at all times makes a full stroke while the stroke of the upper ram 60 19 may be adjusted so that it may have the full stroke of rod 61 or a plurality of shorter lengths or no movement at all.

In the modification illustrated in Fig. 4, 65 greater flexibility of operation is obtained by providing, in addition to the lost motion

connection associated with the upper ram 19, a lost motion connection for the lower ram 20. As in the construction of Fig. 3, a single driving rod 61 is connected at its upper end to the main ram driving mechanism 70 in a manner similar to that described above in connection with Fig. 1. Reciprocating motion is transmitted from the rod 61 to the ram 19 through a lost motion arrangement which is identical with that 75 shown and described in connection with Fig. 3, with the exception that the stop 66 is made adjustable along the rod 61 by means of a pin 70 which passes through the stop 66 and holes 69 in rod 61. By changing 80 the position of the stop 66 the uppermost position of the ram 19 in the retort may be varied to meet varying conditions of operation.

The lower ram 20 is actuated by the reciprocation of rod 61 through a lost motion connection similar to that employed for the actuation of the upper ram 19. As shown, the ram 20 has a depending lug 72 having an eye 73 in which the rod 61 may freely 85 slide. Stops 74 and 75 are adjustably secured to the rod 61, as by bolts 76 and holes 77 in rod 61, the holes 77 being spaced along the rod in such manner that the operating position of both the stops 73 and 90 74 may be readily set in desired positions.

In this embodiment, both the position and length of stroke of each of the auxiliary rams 19 and 20 may be adjusted independently one of the other, and the stroke length 100 of the rod 61 varied by an adjustment of the stops 26 and 27, which are accessible from the front of the stoker. This arrangement provides for the actuation of both of the rams 19 and 20 by a single rod 61 and permits any desired relative stroke length 105 between the two auxiliary rams at any desired portions of the retort.

This flexibility of adjustment has been found advantageous in stoker installations 110 where, because of fuel supply shortage or for any other reasons, fuels of widely varying character are employed in the same stoker. The character of the fuel to be burned being known, a setting of the adjustable members of the auxiliary ram actuating mechanisms may be had which gives the maximum efficiency for that fuel.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In an underfeed stoker, a retort, a main 130

- ram and two auxiliary rams in the retort, a driving means for the main ram, an extendible rod, means comprising a lost motion connection for securing the extendible rod 5 to the main ram driving means, means for operatively securing one of the auxiliary rams to the extendible rod, and a lost-motion mechanism associated with the extendible rod for transmitting to the other of the 10 auxiliary rams a stroke of lesser length than is transmitted to the one auxiliary ram.
2. In an underfeed stoker, a retort, a main ram delivering fuel into the retort, a driving mechanism for the main ram, two auxiliary rams in the retort, an extendible rod, means comprising an adjustable lost-motion connection for securing the extendible rod to the main ram driving mechanism, means for operatively securing one of the auxiliary 15 rams to the extendible rod, and a lost-motion mechanism associated with the extendible rod for transmitting to the other of the auxiliary rams a different stroke length than is transmitted to the one auxiliary ram.
- 20 3. In an underfeed stoker, a retort, a main ram delivering fuel into the retort, a driving mechanism for the main ram, a plurality of auxiliary rams, extendible means having a lost-motion connection with the main ram 25 driving means for actuating the auxiliary rams, and a lost-motion connecting means associated with the extendible means for effecting different stroke lengths to adjacent auxiliary rams.
- 25 4. In an underfeed stoker, a retort, a main ram delivering fuel into the retort, a driving mechanism for said main ram, two auxiliary rams in the retort, a rod connected at one end to one of said auxiliary rams, an adjustable lost-motion mechanism connecting the other end of said rod to the driving mechanism, and adjustable lost-motion mechanism associated with said rod for transmitting to the other of said auxiliary rams a different stroke length than is transmitted to the said one auxiliary ram, the said lost-motion devices being so constructed and disposed that for all adjustments the extreme forward position of each of the rams 40 is the same.
5. In an underfeed stoker, a retort, two auxiliary rams in the retort, and means for reciprocating one ram, means connected to the aforesaid means for reciprocating the second ram, the connection between the two 45 said means including an adjustable lost motion device, said lost-motion device being so constructed and disposed that for all adjustments of said lost-motion device the extreme forward position of each ram is the 50 same.
6. In an underfeed stoker, a retort, two auxiliary rams in the retort, a hollow rod secured at one end to one of said rams and at the other end to the driving mechanism of 55 said stoker, a second rod connected to the other of said rams and extending into the hollow of said first rod, and a lost motion connection between said rods.
- In testimony whereof, I have hereunto 60 subscribed my name this 7th day of May 1923.

OTTO ARAM.
